SWINGING CLOSURE HOLDER AND LOCK

Loyal H. Britton, Indianapolis, Ind.

Application February 3, 1933. Serial No. 654,997

2 Claims. (Cl. 292—275)

The object of this invention is to provide a device for holding hinged closures such as garage and other doors, casement windows and the like, in open or closed position.

5 Another object is to provide a device for locking the door in closed position, and a further object is to provide a device which will be simple to install and to operate, which will be cheap to manufacture and which will be durable.

10 I accomplish the above, and other objects, which will hereinafter appear by the mechanism illustrated in the accompanying drawing, in which—

Fig. 1 is a perspective view of a garage equipped 15 with my invention on the door and in which the door is in open position;

Fig. 2 is a detail showing my device in the same position as in Fig. 1, but on a larger scale and detached from the building and the door, and

20 Fig. 3 is a detail in side elevation of the parts of the door-end of the holding bar with the wall loop in the position occupied by it when the door is closed and showing the loop locked to the bar.

Like characters of reference indicate like parts 25 in the several views of the drawing.

The garage wall has an opening with a frame 4 which opening is closed by a hinged door 5. Bolted to the inner side of the door is a plate bearing a staple or eye 6, and bolted to the top of the door-frame in a corresponding position is a 30 U-shaped loop 7. The bottom portion of the loop extends laterally and somewhat downwardly for reasons hereinafter apparent, and hinged to the rear side of the loop is a pawl-plate 8 which is lifted by a cord 10 threaded through screw 35 eyes 9, 9. Swinging by the frame of the door at the end of the cord is a handle 11 by which the cord is drawn downwardly manually to lift the pawl.

40 A brace bar 12 is bent at one end into a hook 13 which is hooked into the eye 6. The sides of the hook are substantially parallel and are kept from spreading apart by a band 14 which also holds the hook in the eye. The short stem of 45 the hook is bent to form a hump 15 that nearly closes the entrance after the band 14 is placed. Formed in the top of the rod near the hump 15 is a ratchet notch 16. The band 14 is adjustable longitudinally of the stem to vary the resiliency 50 of the free end of the stem.

Near, but not at the opposite end of the bar from hook 13 are two bends forming a shoulder 55 17 in the same plane as the hook 13. The bar is continued parallel with the axis of the rod for a short distance and terminates with a lateral end 18 formed by bending the rod at right angles. This end of the rod in assembling the device is threaded through the loop 7 as shown in the drawing.

60 When the door is closed the loop 7 is forced

past the tapering hump 15 and the hump holds the door in closed position against all ordinary exertions to open it, but a vigorous pull will force the loop out again past the hump, unless held by the engagement of the pawl plate 8 in the 65 ratchet notch 16.

The lateral downwardly sloping extension of the loop 7 causes the bar 12 to enter the extension by gravity where the shoulder 17 will be held against ordinary wind pressure on the 70 door. The pawl plate 8 resting on the bar also aids in holding shoulder 17 in the loop.

When it is desired to open the door the pawl plate 8 is disengaged from notch 16 by a downward pull on the handle 11. The handle may be 75 held down at times by hooking it on a nail 18'. The door when released is opened until the shoulder 17 is drawn through the loop 7 and the loop will lock the door against closure under all ordinary stresses, but will release upon sufficient 80 pressure easily applied manually to the free edge of the door. The bent end 18 keeps the rod from being completely withdrawn from the loop so long as the other end is hooked to eye 6.

I have herein described and illustrated a preferred embodiment of my invention, but it will be obvious and I want it understood that various changes in structure and the relative arrangement of parts may be made within the spirit of the invention and scope of the appended claims. 85 90

What I claim is:

1. In controlling means for swinging closures, the combination with a swinging closure having an eye and a closure frame, of a member depending from the frame, a bar having a hook at one end engaging the eye, said hook having a short stem with a hump in the stem restricting the space between the stems, means for preventing the spreading of the short stem away from the bar adjustable in distance from the end of the stem, said bar passing through an opening in the member depending from the frame and retarded by contact between the depending member and hump. 95 100

2. In controlling means for swinging closures, the combination with a swinging closure having an eye and a closure frame, of a member depending from the frame, a bar having a hook at one end engaging the eye, said hook having a short stem with a hump in the stem restricting the space between the stems, means for preventing the spreading of the short stem away from the bar, said bar passing through an opening in the member depending from the frame and means for retarding the return of the bar through the 115 depending member to prevent the closing of the closure, and means for locking the bar and depending member together to lock the closure. 110 120
